BOOT-LEG FORM.

1,313,505.

Specification of Letters Patent.

Patented Aug. 19, 1919.

Application filed June 13, 1918. Serial No. 239,844.

To all whom it may concern:

Be it known that I, ARTHUR SCHOSHUSEN, a citizen of the United States, residing at Pittsburg, in the county of Crawford, State of Kansas, have invented certain new and useful Improvements in Boot-Leg Forms, of which the following is a full and exact specification.

The present invention relates to form devices for boots or shoes, and the primary object in view is to provide an improved construction of form for the leg portions of finished boots or shoes when these are prepared for display purposes. Accordingly, I have devised a neat and compact design of form adapted to serve as a filler for holding the boot leg distended in the approved flat shape as the leg is laced up or otherwise fastened to the form.

It is a further object of the invention to provide a form construction having suitable means of adjustment for accommodating the form to slight differences in sizes of boot legs, and also for assuring in each instance a proper snug fit of the form when placed in position. For accomplishing this purpose I provide a construction permitting both a longitudinal and a lateral adjustment of the parts comprising the form, whereby varying lengths of both legs are brought within the range of the form and the same made expandible to conform to the width of the boot leg.

It is also an object of the improvements to provide a form of the character described which is adapted to be associated with the common type of boot or shoe follower, the form having provision for embracing the follower and serving, in effect, as a neat and continuous extension of the follower for filling out the leg portion of the boot in the required manner.

It is also sought to device a construction of an extremely simple character for embodying the improvements, comprising a minimum number of parts adapted to be cheaply constructed out of inexpensive material.

With these general objects in view, the invention will now be described by reference to the accompanying drawing illustrating a practical form of embodiment of the improvements, after which the features therein deemed to be novel will be set forth and defined in the appended claims.

In the drawing—

Figure 1 is a side view of a boot, with its upper partly broken away and in section for the purpose of showing a form constructed in accordance with the present invention and fitting within the leg portion of the boot;

Fig. 2 is a vertical section taken on the line 2—2 of Fig. 1;

Fig. 3 is a plan view of the form, on an enlarged scale;

Fig. 4 is a similar view of a modified form of construction; and

Fig. 5 is a transverse section taken on the line 5—5 of Fig. 3.

Referring to the drawing in detail, I have illustrated the improvements in connection with a boot 6 within which is fitted a follower 8 of well-known form, filling out the foot portion of the boot. For forming an extension to this follower, and distending the leg portion of the boot, I provide a form comprising a holder portion made in two sections 10 connected by a rivet or equivalent fastener 12, and adapted to embrace the top portion of the follower 8 by fitting over the sides thereof, as shown in Figs. 1 and 2. These sections 10 extend far enough down to underlie the counter portion of the boot at each side of the follower, so that a more or less gripping action will be exerted upon said sections for holding them in place when the boot is laced. The front and rear margins of the sections 10 are shaped to conform to the general contour of the instep and heel, respectively, of the boot, and these sections, as well as the remaining parts of the form are preferably constructed of stiff sheet material, such as light fiber board or the like.

Mounted between the upper ends of the sections 10 is a pair of side members 14 forming the laterally expandible elements of the form, the same being folded along lines corresponding to the front and rear lines of the boot leg with which they are designed to engage. The said members 14 are folded over the opposite side margins of a longitudinally adjustable member 16, the length and range of adjustment of which are such as to enable the same to accommodate the form to that range of sizes for which the particular form is designed. The side margins of said member 16 extend in upwardly diverging relation, following the

general outline of the boot leg, and the upper side edges of said member act substantially as continuations of the side edges of the members 14. Obviously, therefore, any downward movement of the member 16 will operate to spread said members 14; and vice versa, upward shifting of the member 16 will allow the side members 14 to move toward each other to contract the form. The several elements 14 and 16 are connected slidably to the holder sections 10 by means of a detachable fastener 18 passing through slots 20 and 22 formed in the overlapping portions of the members 14 and 16, respectively, the slots 20 extending transversely or laterally and the slot 22 extending upwardly or longitudinally, thereby permitting the expanding or contracting movements just referred to. The fastener 18 is shown as having a split shank (Fig. 5) adapted to be spread over a washer 24 for holding the parts in assembled relation. The sections 10 of the holder are spaced apart slightly by means of a spacing washer 26 carried by the fastener 12, so as to permit sufficient freedom of movement of the elements carried by the fastener 18.

It will thus be seen that a neat, simple and compact arrangement and construction have been devised for carrying out the desired objects of the invention. The form is adjusted into approximately correct position before the leg portion of the boot is laced, the holder sections being fitted over the top of the follower 8, with the front edges of said sections meeting along the instep line of the follower; with said edges held thus, the form is swung back into the boot leg as far as it will go, seating the holder snugly over the heel portion of the follower and projecting each section of the holder part way between said follower and the boot counter at each side thereof, whereby the holder sections will be firmly gripped between these comparatively rigid portions of the boot and its follower. While the boot is being laced the longitudinally adjustable member 16 remains extended, projecting above the upper end of the boot leg as indicated by the broken lines in Fig. 1, and as soon as the lacing is completed said member 16 is pushed down into the boot leg as shown by the full lines in said figure; this effectually expands the sections 14 to take up any slackness in the boot leg, and the upper wider part of the member 16 of course enters the top portion of the boot leg and maintains the same stretched to its full extent. The member 16 is designed to be completely inclosed and hidden within the boot leg so that none of the form will be visible after the boot is laced. In this way it will be apparent that a light and efficient form construction is obtained which is nicely ad-

justable for fitting tightly and snugly 65 within the boot leg, the adjustable sliding arrangement of the parts enabling the device to expand until the boot leg is fully stretched, and the pivotal connection of said parts allowing such angular adjustment as 70 may be necessary for accommodating the form to the boot leg after positioning the holder upon the follower. A detachable connection is made between the holder and the other parts of the form so that the same 75 holder may be used with different sizes of said other parts, thus accommodating the form to whatever range of sizes of boots may be desired.

In Fig. 4 is illustrated a modified construction, comprising a holder portion, the sections 10' of which are connected by fasteners 30 engaging slots 32 formed in a longitudinally sliding folded section 34, which in turn is connected by similar fasteners 36 85 and slots 38 with a second longitudinally sliding section 40, the latter sliding between the folds of the middle section 34, and the section 34 being received between the sections 10' of the holder portion. This gives 90 a construction in which the elements 34 and 40 are longitudinally adjustable for accommodating the form to the length of the boot leg, while at the same time a certain degree of expanding action, *i. e.*, relatively to the 95 boot leg, is obtained by the downward movement of said elements (by virtue of their tapered outline), thereby accommodating the form to the width of the boot leg.

While I have illustrated by means of the foregoing structural details what are now deemed to constitute practical and satisfactory embodiments of the improvements, I desire to expressly reserve the right to make all such formal changes or modifications as 105 may fairly fall within the scope of the appended claims.

What I claim is:

1. A boot leg display form comprising a plurality of elements arranged in continuously overlapping relation and adjustably connected for relative expanding or contracting movement for fitting snugly within the leg portion of the finished boot. 110

2. A boot leg display form comprising a plurality of longitudinally expansible elements arranged in continuously overlapping relation and provided with means slidably connecting said elements and permitting adjustment thereof to correspond with the 115 length of the boot and fit snugly within the leg portion thereof. 120

3. A boot leg display form comprising a plurality of longitudinally and laterally expansible elements provided with a single 125 connecting member permitting adjustment of said elements to fit snugly within the leg portion of the finished boot.

4. A boot leg display form comprising a plurality of relatively movable elements all overlapping each other, and a single member slidingly connecting said elements and permitting relative longitudinal and lateral movement thereof for fitting snugly within the leg portion of the finished boot.

5. A boot leg form comprising laterally expansible elements and a longitudinally adjustable member operable to expand said elements and also to adjust said form to the length of the leg portion of the boot.

6. A boot leg form comprising a holder portion, and a pair of laterally expansible elements and a longitudinally adjustable member slidingly connected to said holder portion, said longitudinally adjustable member being operable to adjust said form to the length of the leg portion of the boot while simultaneously actuating said expansible elements to conform to the width of said leg portion.

7. A boot leg form comprising a holder portion, and a plurality of laterally and longitudinally adjustable elements provided with a combined sliding and pivotal connection to said holder, said elements being

adjustable to fit snugly within the leg portion of the finished boot.

8. In a boot leg form, the combination with a follower, a holder adapted to embrace said follower, and a plurality of relatively movable elements carried by said holder and adjustable for fitting snugly within the leg portion of the boot.

9. In a boot leg form, the combination with a follower, a holder adapted to embrace said follower, and a plurality of longitudinally and laterally expansible elements carried by said holder and adjustable for fitting snugly within the leg portion of the boot.

10. In a boot leg form, the combination with a follower, a holder adapted to embrace said follower and having extensions projecting into position to be clamped between said follower and the counter portion of the boot, and a plurality of relatively movable elements carried by said holder and adjustable for fitting snugly within the leg portion of the boot.

In witness whereof I hereto affix my signature.

ARTHUR SCHOSHUSEN.
